UNITED STATES PATENT OFFICE

2,588,222

ICE CUBE SUPPORT

Eloy D. Ekkebus, John C. Gallagher, and Raymond Zappel, Chicago, Ill., assignors to Allis Rubber Corporation, Chicago, Ill., a corporation of Delaware

Application July 23, 1949; Serial No. 106,394

2 Claims. (Cl. 62—108.5)

1

Our invention relates to an improvement in ice cube supports and has for one purpose to provide an improved support in which ice cubes may be frozen and stored and from which they can be dispensed.

Another purpose is to provide an improved ice cube storage means from which ice cubes can be removed in less quantity than the total quantity undergoing simultaneous storage. Another purpose is to provide an improved individual container in which ice cubes may be frozen and stored in twos or in multiples of two. Another purpose is to provide a support for flexible ice cube containers.

Other purposes will appear from time to time in the course of the specification and claims.

We illustrate the invention more or less diagrammatically in the accompanying drawings wherein:

Figure 1 is a perspective view of an embodiment of the invention;

Figure 2 is a section on the line 2—2 of Figure 1;

Figure 3 is a plan view;

Figure 4 is a side elevation with parts broken away and parts in vertical section;

Figure 5 is a perspective view of an individual ice cube container; and

Figure 6 is a section on the line 6—6 of Figure 5.

Like parts are indicated by like symbols throughout the specification and drawings.

Referring to the drawings, we employ a relatively rigid base or support, generally indicated as A, which includes a bottom portion having transversely, longitudinally extending parts 1, connected by an upwardly extending ridge 2. The parts 1 terminate at their outer side edges in downwardly turned flanges or runners 3. The lower edges of the flanges 3 terminate in a single horizontal plane and are adapted to serve as runners or supports which engage the bottom of the freezing sleeve or container into which the support A may be inserted. It may, for example be the container of the conventional ice cube freezing compartment of a household refrigerator. The support A is shown as having a front wall 4 and a rear wall 5. These may be of any suitable material and are preferably connected at top and bottom to the portions 1 of the member A, and also to the upwardly extending longitudinal ridge 2.

Mounted on the base A, and between the end walls 4 and 5, are a plurality of individual ice cube containers. These containers are prefer-

2

ably of flexible, easily distortable material, such as rubber or a rubber substitute, or a suitable plastic. Since we employ a central ridge 2, it is advantageous to have the individual containers 5 B made to receive two ice cubes, one being located on each side of the ridge 2. It is to be understood, however, that they may be made in multiples of two. For example, it may be practical to have four or five individually removable containers each having space for two ice cubes at each side of the ridge 2.

We illustrate, in Figures 1 and 5, ice cube containers B, each of which has two cube receiving pockets. Referring, for example, to Figure 5, the container B is shown as having individual pockets, 10, 11, properly sized and shaped to form an ice "cube." For convenience in removal, the pockets are preferably upwardly enlarged. The member B is shown as having cross walls 12, 13, connected by side walls 14, 15, and by bottom walls 16. The two pockets are connected by a bridge or intermediate wall portion 17 which branches to form two inside walls 18, 19. The space between the walls 18, 19 is preferably formed and proportioned to provide a reasonably snug fit over the ridge 2 of the base A. However, the area of adhesion may be reduced, or even substantially eliminated, if desired.

It is important, however, that the bridge 17 overlie or span the ridge 2, and that the bottoms of the two compartments engage the upper surfaces of the support members 1, as shown in Figure 2. It may be advantageous to localize the area of contact. For example, we may employ any suitable bottom ridges or downward projections 20. It may also be advantageous to have outwardly extending flanges 21 at the upper ends of the side walls 14, 15, as shown in Figures 2 and 5.

The arrangement of the individual containers B on the base A is indicated, for example, in Figures 1 and 2.

Whereas we have shown a practical and operative embodiment of our invention, it will be understood that many changes may be made in size, shape, number and disposition of parts without departing from the spirit of the invention. We therefore wish our description and drawings to be taken as in a broad sense illustrative or diagrammatic rather than as limiting us to our specific showing herein. For example, whereas we illustrate runners 3 for supporting the supporting element for ready removal from a sleeve or evaporator, it will be understood that other means or other shapes of downward projection

may be employed, for providing a limited area of contact, and for thereby permitting the support to be withdrawn, sled-like, from the sleeve or refrigerating surface upon which it is supported.

The use and operation of our invention are as follows:

We employ a relatively rigid supporting base A which is adapted to be slidably inserted into any suitable sleeve or refrigerating container. It is preferably of the same general size and proportions as the ice cube trays which are customarily used in domestic refrigerators. It may thus readily be sold as a replacement for the conventional ice cube trays, to be used in previously sold refrigerators or it is adapted for use in new equipment. It is frequently advantageous to be able to remove a smaller number of ice cubes than are actually frozen in or stored in the conventional ice cube tray. We find it advantageous to employ individually removable sub-containers as shown at B, which can be removed and emptied of ice and can thereafter be refilled with water and returned to the support A. This entirely avoids the necessity of breaking out the ice cubes from an entire tray. It also provides a very ready and convenient means for removing the number of ice cubes which are to be used. If, for example, in a small household, it is desired to provide ice for two drinks, the user need only remove one of the units B from the support A, leaving the support A in the refrigerator. Since the container is preferably formed of flexible and readily distortable material, it is a very simple matter to remove the frozen ice cubes. Very slight thawing, or no thawing at all, and a slight twisting or bending of the unit is all that is necessary. The user can then immediately refill the compartments 10 and 11 with water and return the unit B to the support A. We find it desirable to employ a somewhat larger cavity than is employed in any conventional ice cube trays. Thus a large piece of ice is provided which is adequate to cool a drink.

The fact that the two ice pockets are located at opposite sides of the ridge 2 makes it easy to remove or apply the units B. The central bridge 17 is a convenient handle, unless the pockets are filled to the top. The flanges 21 also assist both in handling and in twisting or bending the unit to free the ice cubes. There is a minimum possibility of freezing the support A to the freezer sleeve, because of the small surface contact insured by the runners 3. There is a minimum chance of freezing the units B to the support A because of the use of spacing supports 20. It will further be understood that the snug contact shown in Figure 2 between the ridge 2 and the opposed walls of the pockets may be avoided by similar spacing means.

We claim:

1. In an assembly for freezing and dispensing ice cubes, a support adapted for slidable insertion into a freezing sleeve, a flexible ice cube container adapted to contain a plurality of ice cubes removably mounted thereon, said support including a bottom wall and upstanding end walls but being free of cube container supporting side walls, a longitudinally extending ridge upstanding from said bottom wall along substantially the center thereof, said cube container being mounted on said ridge and having cube compartments on each side of said ridge, the cube container having supporting engagement with the bottom wall and with said longitudinally extending ridge only.
2. In an assembly for freezing and dispensing ice cubes, a metal ice cube container support adapted to be slidably inserted into a freezing sleeve, said support including a bottom wall having sleeve engaging portions bent downwardly along the longitudinal side edges thereof, said support having also an upwardly and longitudinally extending ridge located substantially midway between the side edges of the support but being free of cube container supporting side walls, said ridge being substantially frustroconic in transverse cross section, and a plurality of flexible ice cube containers arranged along said support and having supporting engagement with said bottom wall and said ridge only, said ice cube containers being upwardly removable therefrom, each said container having cube compartment portions located at opposite sides of said ridge, with a connecting portion spanning said ridge and adapted to be supported thereby.
